UNITED STATES PATENT OFFICE.

GEORGE CROUCH, OF NEW YORK, N. Y.

TRUNK OR CASE.

SPECIFICATION forming part of Letters Patent No. 371,554, dated October 18, 1887.

Application filed February 23, 1887. Serial No. 228,606. (No model.)

To all whom it may concern:

Be it known that I, GEORGE CROUCH, a citizen of the United States, and a resident of New York, in the county of New York and State of New York, have invented new and useful Improvements in Trunks or Cases, of which the following, taken in connection with the accompanying drawings, is a specification.

This invention relates to improvements in trunks or cases; and it consists in providing the body or cover, or both, thereof with corrugations made integral with such body or cover, and also in the combination, with such corrugations, of filling-strips seated in said corrugations and held in place therein by means of a lining secured to the inside of the trunk body or cover, for the purpose of combining in a trunk or case great strength, durability, and lightness, as will hereinafter be more fully shown and described.

In the accompanying drawings, Figure 1 represents a perspective view of my improved trunk, and Fig. 2 represents a horizontal section of the same. Fig. 3 represents a perspective sectional view of the invention as applied to telescopic or other cases.

Similar letters refer to similar parts wherever they occur on the different parts of the drawings.

A in Figs. 1 and 2 is the body of the trunk, made of vulcanized fiber or paper, stout paper-board, leather, rawhide, or analogous material, and said body is molded with the corrugations A' A' A', as shown in said Figs. 1 and 2, such corrugations having their convex surfaces on the outside and their concave surfaces on the inside of the trunk, as shown. Within such corrugations I lay filling-strips B B B, made of wood or corrugated metal, and to the interior of the corrugated trunk-body I glue or otherwise secure a lining, C, of wood, paper-board, or analogous material, as shown in Fig. 2.

The cover of the trunk is constructed in the same manner as the trunk-body above described. The lining C may be made of one or more layers, as may be desired.

D D are the bunters or corner-caps, as usual.

E E are the angle-pieces of the trunk-body, as is usual in trunks.

F is the joint at the upper portion of the trunk-body in the ordinary manner.

By corrugating the body and cover of the trunk and placing in such corrugations the filling-strips B B and covering the trunk on the inside with the lining C, as above described, I produce a trunk of exceedingly great strength combined with lightness, and it can be manufactured at less price and is far superior to trunks in which corrugated strips are made independent of the trunk body or cover and afterward riveted or otherwise secured to the same.

In Fig. 3 I have represented a telescopic case composed of the body portion G and cover G', which may be made of any suitable materials—such as vulcanized fiber or paper, stout paper-board, rawhide, leather, or analogous materials—such body and cover being molded with the corrugations g g, as shown in said Fig. 3.

I do not wish to confine myself to the number of corrugations on each side, top, or bottom of said trunks or cases. They may also be made and arranged in any suitable direction on such trunks or cases without departing from the essence of my invention.

Having thus fully described the nature and construction of my invention, I wish to secure by Letters Patent, and claim—

A trunk or case formed with the corrugations A' A' A' in its shell, combined with the filling-strips B B B, seated in said corrugations, and lining C, all arranged and constructed substantially in a manner and for the purpose set forth.

In testimony whereof I have signed my name to this specification, in the presence of two subscribing witnesses, on this 11th day of February, A. D. 1887.

GEORGE CROUCH.

Witnesses:

WM. G. CONKLIN,
WALTER F. DEXTER.
